US00D887472S

(12) **United States Design Patent** (10) **Patent No.:** **US D887,472 S**
Chen (45) **Date of Patent:** **** Jun. 16, 2020**

(54) **CAMERA**

(71) Applicant: **SZ DJI Technology Co., Ltd.**,
Shenzhen (CN)

(72) Inventor: **Yiwei Chen**, Shenzhen (CN)

(73) Assignee: **SZ DJI Technology Co., Ltd.**,
Shenzhen (CN)

(**) Term: **15 Years**

(21) Appl. No.: **29/720,212**

(22) Filed: **Jan. 10, 2020**

Related U.S. Application Data

(63) Continuation of application No. 29/654,663, filed on Jun. 26, 2018, now Pat. No. Des. 874,531.

CLAIM

The ornamental design for a camera, as shown and described.

DESCRIPTION

This application is cross-reference related application, each of which is also incorporated herein in its entirety by reference thereto:

U.S. application Ser. No. 29/654,658, titled "Aerial Vehicle"

U.S. application Ser. No. 29/654,662, titled "Battery"

U.S. application Ser. No. 29/654,665, titled "Camera With Gimbal"

FIG. 1 is a top front perspective view of a camera showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the camera that form no part of the claimed design.

1 Claim, 4 Drawing Sheets
